UNITED STATES PATENT OFFICE.

CHARLES LEA, OF BOSTON, MASSACHUSETTS, ASSIGNOR TO SHAWMUT ENGINEERING COMPANY, OF BOSTON, MASSACHUSETTS, A CORPORATION OF MASSACHUSETTS.

MACHINE FOR SPLICING THREADS.

1,408,705.

Specification of Letters Patent.

Patented Mar. 7, 1922.

Application filed October 7, 1915, Serial No. 54,698. Renewed May 25, 1921. Serial No. 472,556.

To all whom it may concern:

Be it known that I, CHARLES LEA, citizen of the United States, and resident of Boston, Massachusetts, have invented certain new and useful Improvements in Machines for Splicing Threads, of which the following is a specification.

This invention has for its object the splicing together of warp threads or the like by fastening the overlapped ends of two sets of threads by means of metallic clips, and comprises a machine for automatically and expeditiously feeding and binding said clips upon the successive warp threads of the series that are to be fastened together.

In general the invention embraces a travelling carriage mounted to traverse the rack bar which forms a spacing means for the two sets of threads to be joined, combined with means for automatically advancing the carriage and with clip feeding and setting mechanism automatically operated in proper correlation to the movement of the carriage, as will be hereinafter explained. Other features of the invention have relation to the provision of means for automatically stopping the carriage at any predetermined point for locking or setting the carriage in proper registry with the rack bar during each clip-setting operation, as well as other subordinate features of improvement which will be more particularly explained in this specification and defined in the claims annexed hereto.

In the accompanying drawings is shown the preferred form embodying the principles of this invention, in which

Figure 1 is a side elevation of the complete device mounted on the rack bar.

Figure 2 is an end elevation of the same, partly broken away to show working parts.

Figure 3 is a longitudinal central section showing details of the plunger or clip-setting mechanism in connection with the carriage locking device.

Figure 4 is a front elevation of the clip-feeding and shearing elements.

Figures 5 and 6 are detail views showing respectively the open or unset clip and the clip after it has been set or clamped around the threads.

Figure 7 is a plan view in cross section through the lower part of the carriage showing the carriage-feeding and clip-feeding devices and the means for removably locking the carriage bed to the supporting rack bar.

Figure 8 is a side elevation of the adjustable carriage retaining bar.

Figures 9, 10 and 11 are detail views showing the means for automatically stopping the carriage at a predetermined point.

Figure 12 is a cross section showing the guide and runway through which the strip forming the clips is fed to the plunger or setting die.

Figure 13 shows a rear view of the wave cam or interrupted worm forming the driving element of the carriage shifting mechanism.

Generally speaking, the machine comprises a travelling carriage adapted to be removably mounted upon a longitudinal rack bar whose equally spaced teeth serve as spacing guides for receiving the overlapped ends of two series of warp threads to be united by the clips. The moving parts of the actuating mechanism are driven from a motor-driven shaft mounted on the carriage. One train of mechanism operates to shift the carriage step by step along the rack bar. Another train of mechanism acts to intermittently feed the strip of fastening clips to the successive spaces on the rack bar. Still another train of mechanism actuates a reciprocating clip-setting plunger or die to clamp or set each clip upon its warp thread after shearing it from the strip.

In the form illustrated, I provide a carriage *a* comprising a longitudinal bed having interlocking or dove-tailed engagement with a supporting rack bar *b*, as best shown in Figures 1 and 2. To the rack bar are fastened brackets *b*² which serve to hold the spacing clamps which have previously been secured to the ends of each series of warp threads but which form no part of the present invention. At one end of the carriage *a* I provide a vertical frame or upright portion *a*' formed with vertical ways to receive a reciprocating cross-head *a*² in which is mounted a vertical plunger or die *c* which is adjustably fastened to the cross-head by a screw and slot connection *c*'. A vertically adjustable thrust screw *c*² serves to form a positive stop to prevent the vertical displacement of the die or plunger *c*. The lower end of the die or plunger *c* is concaved while the bottom of the spaces between the teeth of the rack bar *b* is rounded or concaved so that the clip *x* will be forced down around the outside of the threads and clinched around them by the

continued downward movement of the plunger, according to the form indicated in Figure 6.

A motor d is mounted in suitable bearings on the carriage and its shaft d^1 carries at one end a worm d^2 intermeshing with a worm gear e' on the horizontal shaft e , to which shaft are secured crank pin disks e^2 , whose pins e^3 are operatively connected with

10 pin a^3 on either side of the cross-head in order to reciprocate said cross-head.

On one end of the shaft e is secured an interrupted spiral gear or wave cam f whose thread or blade is perpendicular to the axis 15 of the shaft for the greater part of its circumference but is deflected laterally for a short distance so as to impart an intermittent movement to the intermeshing spiral gear f' at each revolution of the shaft e .

20 The spiral gear f' is secured to the end of the vertical shaft f^2 which carries at its lower end a helical gear f^3 meshing with a helical gear f^4 on the horizontal shaft f^5 mounted in the bed of the carriage. On the 25 shaft f^5 is secured a pinion f^6 which intermeshes with the rack teeth b' of the rack bar b upon which the carriage is supported. Each step in the intermittent rotation of the pinion f' serves to advance the carriage 30 one tooth along the rack bar b .

As it is desirable that the clip-setting plunger a' should register perfectly with the space between each pair of adjacent teeth, I provide means for locking the carriage so as to prevent accidental displacement when the die is operating and also to secure perfect registration with the spaces between the rack teeth. To this end I provide (Figure 3) a diagonal plunger f^7 , 40 one end of which normally projects into the pathway of the reciprocating cross-head a^2 , while the other end is provided with tapered teeth f^8 adapted to interlock with each successive tooth of the pinion f^6 . This locking plunger is normally withheld from engagement with the pinion by means of a retractile spring f^9 which allows the plunger to descend under pressure from the descending cross-head a^2 and retracts the plunger 45 when the cross-head reaches the upper part of its traverse. It will be seen that before the clip-setting plunger enters the rack bar the registering and locking device has already been actuated to secure the exact 50 registration between the plunger and the space into which the clip next to be acted upon by it is dropped. The mechanism is so timed that the carriage-advancing cam f begins to move only after the plunger is 55 raised clear of the rack bar.

As shown in Figure 4, the clips x are formed of a continuous strip of metal, each clip in alternation comprising two prongs on one side and a middle prong on the opposite

side. The clips are engaged by the successive teeth g' formed in alternation on opposite sides of the feed wheel g . The clip strip rests astride of a guide plate g^2 over which it advances into the vertical groove or way in which the plunger c reciprocates. The feed wheel g is mounted on a longitudinal shaft g^4 to which is secured a clutch member g^5 adapted to be moved into positive clutching engagement with the cooperating member g^6 when the shaft g is pushed to 75 the left. The clutch member g^6 is loose on the shaft g^4 and has a bevelled gear member g^7 engaging a beveled gear g^8 which is loose on the shaft f^5 and is driven by a spur gear g^9 which is forced into clutching 80 engagement with the inside face of the bevel gear g^8 by means of the spiral spring g^{10} . As shown in Figure 1, the spur gear g^9 is engaged by a sector arm or lever g^{11} pivotally mounted on the pivot pin g^{12} carried 85 by the upright portion of the frame and which has an angularly extended arm g^{13} engaging a roller g^{14} mounted on one of the pins a^3 of the reciprocating cross-head mechanism. As shown in Figure 7, the teeth g^{20} forming the connecting driving clutch between the pinion g^6 and the bevel gear g^8 are inclined on one side so that the clutch 90 is operative in one direction only. A spring g^{21} acts to maintain the arm g^{13} in operative 95 contact with the roller g^{14} while also acting to return the lever g^{11} to its initial position at the left when the cross-head is descending. This train of mechanism therefore acts to give an intermittent or step by step rotation to the shaft g^4 and the clip-feeding wheel g at each complete stroke of the 100 cross-head.

In order to permit the carriage to be advanced along the rack bar to any predetermined point before beginning to feed the clips, the shaft g^4 is made adjustable longitudinally so as to throw its clutch member g^5 into or out of operative engagement with the driving clutch member g^6 . By merely 105 shifting the shaft longitudinally, therefore, the clip-feeding mechanism may be rendered operative or inoperative. To secure proper registration of the clip with the plunger passage or slideway, and also to prevent accidental rotated displacement of the feed wheel, I secure to the shaft g^4 a registering hub or member g^{25} provided with axial corrugations on its periphery adapted to be engaged by a spring-pressed member or ball g^{26} located in a retaining tube or arm g^{27} secured to the carriage. This ball yields sufficiently to allow the shaft to be rotated 110 step by step by its actuating mechanism and yet holds it in correct position to insure 115 proper location of the clip for the shearing operation. The spring-pressed ball also acts as a friction pressure to prevent the accident 120

dental longitudinal displacement of the shaft g^4 .

In order that the attendant may be free to leave the machine after it has been started in operation I provide means for automatically stopping the machine when it has completed the work of splicing all the warp threads contained in the rack bar. To this end I provide a bracket or stop i which has a dove-tailed interlocking engagement with the rack bar, as shown in Figure 9, so that it can be set at any location on the rack bar. This stop bracket i has a bore head or boss i^2 in which is mounted a plunger rod i^2 normally pressed outward by a compressed spring i^3 . This plunger rod is located in alignment with a push button or plunger i^5 which forms the operative member or any appropriate form of electrical switch for making and breaking electric circuit which energizes the motor. In this case, merely for illustration, I have shown the plunger i^5 provided with a projecting boss i^6 adapted to engage one terminal i^7 of the electric circuit, the other terminal being connected directly with the movable plunger itself. A spring detent i^8 serves to hold the plunger or switch member in its inner or outer position by its engagement with notches or serrations on the bottom of the plunger i^5 . The switch box itself i^{10} is, of course, mounted on the carriage. When the carriage has advanced until the switch i^5 abuts against the stop plunger i^2 , the further advance of the carriage serves to push the plunger i^5 inward so that the boss i^6 passes beyond the spring terminal i^7 , thus breaking the energizing circuit. To start the motor again the switch rod i^5 is pulled out by hand, thus closing the contact between the boss i^6 and the spring terminal i^7 . The adjustable stop member i is locked in any desired position of adjustment by means of the spring-pressed ball i^{20} which yieldingly engages two adjacent teeth of the rack bar. The spring yields sufficiently to allow the bracket to be slid along the rack bar by the application of a substantial degree of pressure while it affords a substantially stronger resistance than is required to overcome the resistance of the switch rod i^5 . It results from this arrangement that if the switch should become broken or otherwise inoperative to break the circuit, the stop bracket would yield under the continued pressure of the positively-driven carriage so as to prevent a breakage of the parts. In this way the yielding locking engagement between the stop member and the rack bar acts as a safety or protective device to prevent injury.

The rack bar, of course, may be made quite long to accommodate either a large or a small number of warp threads for wide or narrow goods.

65 The body a of the carriage, is slidingly

locked or retained on the rack bar by means of a dove-tail engagement formed by clamping plates a^{30} secured to the opposite sides of the body a of the carriage and having their lower edges extended down and undercut to form a dove-tail engagement with the flared sides of the rack bar as shown in Figures 4 and 7.

In order to permit the carriage to be readily lifted or disengaged from such dove-tail engagement with the rack bar without having to slide it clear back to one end of the rack bar, I make provision for securing one of these locking bars a^{30} to the body of the carriage by means of a quick releasing connection best shown in Figure 7. To this end the securing screws a^{31} instead of having their heads bear directly against the outer face of the clamping bar a^{30} , actually have their heads abutting against the outer face of a slotted bolt or slide a^{33} interposed between the rack bar a^{30} and the heads of the bolts a^{31} . As shown, the slide bolt or keeper a^{33} has two elongated slots for receiving the shanks of the bolts and across said slotted portions the slide bolt a^{33} is reduced in thickness to form inclined portions as shown at a^{34} , sloping down to thinner or reduced portions of the bolt.

The slide bolt or keeper a^{33} is provided with a handle a^{36} to facilitate its sliding from operative to inoperative position longitudinally of the carriage. Obviously if the bolt is slid toward the left (Figure 7) the thinned or reduced portions of the bolt opposite the slots a^{35} will be interposed between the screw heads a^{31} , and the clamping plate a^{30} , and in this position the bolt heads will not prevent the slide bolt or keeper a^{33} , or the dove-tail clamping plate a^{30} from being moved bodily in a lateral direction away from the body of the carriage, the amount of lateral movement thus permitted, being equal to the difference in thickness between the reduced portions of the bolt adjacent to the slots a^{35} , and the thicker portions of the main body of the bolt. This movement is sufficient to allow the inwardly projecting edge of plate a^{30} to move outward far enough to clear the upper wide portion of the rack bar so as to permit lifting or disengaging the carriage from the rack bar at whatever part of the rack plate the carriage may be situated.

Conversely, the carriage may be replaced on the rack bar at any intermediate point when the slide bolt a^{33} is in the retracted position, and the bar a^{30} may then be firmly locked against the side of the carriage body a , by pushing the bolt to the right, in which operation the inclined faces a^{34} on the outer side of the bolt, act as cam surfaces to force the plate a^{30} inward firmly against the body of the carriage, and to lock it there. It will of course be understood that the screw apertures in plate a^{30} through which the screws

are passed, are of sufficient size to permit the free lateral movement of this clamping plate.

The outward movement of the plate when 5 the bolt is slid to releasing position is assisted by means of the compression springs a^{32} seated in sockets in the body.

The operation of the machine is as follows: The strip containing the connected 10 clips is coiled upon the reel g^{16} and inserted in the runway enclosing the supporting guide plate g^2 which is made adjustable by means of the screw and slot fastening g^{15} with the forward end of the strip projecting 15 into the vertical slot or slideway of the punch c and the feed wheel g in operative engagement with the superimposed clip. The clamping bolt a^{33} is pushed back to allow the clamping plate a^{30} to open outwardly 20 to allow the carriage to be placed at the appropriate point on the rack bar, after which the clamping plate is locked by sliding the bolt into locking position. When the machine has been set with the punch in alignment 25 with the recess of the rack bar which contains the first set of threads to be joined, the switch i^5 is moved to close the motor circuit and the machine then starts on its operation. The operator then sets the stop member 30 i at the proper point to throw the switch and stop the motor after the recess containing the last set of overlapped threads has been reached. The rotation of the motor shaft causes the punch to descend to clinch 35 the clip around the threads in the rack bar recess, the plunger f^7 acting during the initial part of the descent of the plunger to automatically register the descending punch with the appropriate rack bar recess. After 40 the clinching operation when the plunger has been raised clear of the rack bar, the registering member f^7 is released and thereafter the carriage is moved forward one step or tooth by the partial rotation of the pinion 45 f^6 . As the cross-head continues its upward movement the clip-feeding wheel is advanced one step to bring the next clip into the slideway of the clip-setting plunger in position to be sheared off and clinched 50 around the next set of threads. This operation continues until the stop-member is reached, when the machine is automatically stopped.

What I claim is:

55 1. A splicing machine for splicing warp threads embracing in combination a thread positioning rack bar, a carriage slidingly supported thereon, automatically driven mechanism mounted on said carriage to actuate it step by step along said rack bar and embracing an electric motor, clip feeding and setting mechanism operatively connected with the carriage moving mechanism and dis-connectable therefrom at will in order 60 to permit movement of the carriage when 65

the clip setting and feeding mechanism is at rest, substantially as described.

2. A device of the class described embracing in combination with a rack bar for holding the threads to be spliced, a carriage movably mounted on said rack bar, automatically operated means for advancing said carriage step by step along the rack bar, clip-feeding and setting mechanism automatically actuated in correlation with the 75 carriage-actuated mechanism to set each successive clip between the intervals of movement of the carriage, and means for stopping the carriage and clip-setting mechanism at a predetermined point on the rack 80 bar, substantially as described.

3. The combination with the rack bar adapted to hold the threads to be spliced, a movable carriage mounted thereon, carriage shifting mechanism, clip-feeding and setting 85 mechanism, a motor and its shaft mounted on said carriage, said shaft having suitably correlated driving connections with the carriage shifting mechanism and with the clip-feeding and setting mechanism whereby the 90 threads in each successive recess of the rack bar are consecutively united, substantially as described.

4. The combination with the thread-retaining rack bar, a movable carriage mounted 95 thereon, driving mechanism mounted on said carriage in engagement with the rack bar to shift the carriage step by step longitudinally of the rack bar, and means for automatically stopping the carriage at a predetermined 100 point on the rack bar, substantially as described.

5. The combination with a yarn-retaining rack bar, a movable carriage located thereon, clip-feeding and setting devices mounted on 105 the carriage, automatic actuating mechanism for operating the carriage and the clip-feeding and setting mechanism in correlation, and means for automatically stopping the actuating mechanism at any predetermined 110 point on the rack bar, substantially as described.

6. In a thread splicing machine the combination with an automatically-operated movable carriage, clip feeding and setting 115 mechanism mounted thereon, a warp positioning rack-bar forming a guide for the carriage and constructed to cooperate with the said clip setting mechanism, a stop member secured to the rack-bar and adjustable thereon and arranged to engage a member controlling the carriage moving mechanism thereby acting to arrest the movements of the carriage and the clip feeding and setting mechanism, substantially as described. 120

7. The combination with a warp positioning rack bar, of a movable carriage, means for slidingly connecting said carriage with the rack bar to permit the carriage to travel longitudinally of the rack bar, means where- 130

- by said connecting means may be engaged with or released from the rack bar at any point intermediate of the ends of the rack bar, and clip-feeding and setting means 5 mounted on said carriage to cooperate with the rack bar in uniting the threads, substantially as described.
8. The combination with a warp positioning rack bar, clip-setting mechanism cooper- 10 ating therewith, a movable carriage for supporting said clip-setting mechanism in operative relationship to the rack bar, longitudinal retaining ribs or plates forming an interlocking and sliding engagement with the 15 rack bar to retain the carriage in position, one of said plates being detachably clamped against the rack bar to permit the carriage to be slidingly locked to and to be released from any part of the rack bar, substantially 20 as described.
9. In a warp splicing machine, the combination with the warp positioning rack bar of the clip-setting mechanism, a travelling carriage mounted on the rack bar, a longitudi- 25 nal plate forming an interlocking connection between the rack bar and the carriage, and means for removably locking said plate into operative retaining position, substantially as described.
- 30 10. In a splicing machine the combination with a yarn-positioning rack bar of a carriage mounted to travel longitudinally thereof, carriage shifting means clip-feeding and setting mechanism mounted on the carriage 35 to cooperate with said rack bar, a yielding stop member adapted to be located at any predetermined point on the rack bar to control the carriage shifting mechanism to arrest the operation of the machine, substan- 40 tially as described.
11. The combination with the yarn-holding rack bar, a travelling carriage, clip-feed- 45 ing and setting mechanism mounted thereon to cooperate with the rack-bar in setting the clips on the yarn, means for advancing the carriage step by step longitudinally of the rack bar, and means for accurately position- 50 ing the carriage to cause the clip-setting mechanism to properly register with the rack bar, substantially as described.
12. The combination with a yarn-position- 55 ing rack bar of clip-feeding and setting mechanism, a supporting carriage movable along the rack bar, carriage shifting mech- 60 anism embracing a pinion in operative engagement with the rack bar, and a carriage- registering and holding device movable into operative relationship with the pinion when the carriage is at rest, substantially as de- 65 scribed.
13. The combination with a yarn position- 70 ing rack bar, a carriage movable along said rack bar, a carriage shifting pinion having operative engagement with the rack bar, a 75 clip-setting plunger mounted on said car- riage, and a registering and locking member movable into operative engagement with said pinion by the descending plunger mecha- nism, substantially as described.
14. In a splicing machine the combination 80 with work-positioning means, of a support- 75 ing carriage, a reciprocating clip-setting plunger movable in a slideway formed in said carriage, mechanism for feeding clips successively into said slideway to be acted upon by the plunger, said mechanism embracing an intermittently movable feed member and an adjustable guide plate arranged adjacent to said slideway, with its forward edge in position to cooperate with said plunger in shearing off each clip, and a rack bar arranged to co-operate with the plunger in setting the successive clips, said rack bar also serving as a guide and positioning means for the carriage, substantially as described. 85
15. The combination of a yarn-holding rack-bar, an automatically movable carriage mounted thereon to travel longitudinally thereof, clip setting and clip feeding devices co-ordinated with the carriage moving mech- 90 anism, said clip feeding device comprising a feed wheel, an actuating shaft therefor operatively connected by means of a shiftable clutch and a spring detent for accurately position- 95 ing said shaft in proper rotative position while yielding to allow the intermittent rotation of said shaft, substantially as de- scribed.
16. A splicing machine embracing in com- 100 bination means for positioning the work to be spliced, an automatically moved carriage, a clip-setting mechanism mounted thereon, an intermittently rotatable feed member adapted to engage and feed successive clips into position to be acted upon by said clip- 105 setting means, said feed actuating means being controlled by the movement of the clip- setting means, the feed actuating means being provided with an adjustment for ren- 110 dering it operative or inoperative at will while the carriage moves, substantially as described.
17. A splicing machine embracing means for positioning the work, a movable car- 115 riage, reciprocating clip-setting mechanism, an oscillating sector lever having oper- 120 ative engagement therewith, a pinion actuated by said sector lever, a rotatable clip-en- gaging feed wheel and its driving shaft op- 125 eratively connected therewith by an in and out clutch engagement, gearing forming an operative connection between said pinion and said feed member shaft to actuate the same intermittently in one direction, a rack bar engaged by said pinion to shift the carriage, substantially as described.
18. The combination with the reciprocat- 130 ing clip-setting member, a feed member lo- cated to engage the clips and feed them in proper relationship to said clip-setting mem-

ber, and means for accurately positioning and retaining said feed member to insure the exact positioning of each clip presented to the clip-setting member, and a yarn-holding rack-bar whose teeth cooperate in succession with said clip setting mechanism to set successive clips, substantially as described.

19. The combination with a rack bar for retaining the warp threads to be spliced, a

clip-setting mechanism cooperating therewith and embracing a reciprocating cross-head, and a punch member adjustably secured in said cross-head in position to clinch the clips upon the threads, substantially as described.

In witness whereof, I have subscribed the above specification.

CHARLES LEA.
